UNITED STATES PATENT OFFICE.

HENRY C. WEEDEN, OF BOSTON, MASSACHUSETTS.

PORTABLE FIRE-WORK STAND.

SPECIFICATION forming part of Letters Patent No. 334,496, dated January 19, 1886.

Application filed September 24, 1885. Serial No. 177,999. (No model.)

To all whom it may concern:

Be it known that I, HENRY C. WEEDEN, of Boston, in the county of Suffolk and State of Massachusetts, a citizen of the United States, 5 have invented certain new and useful Improvements in Portable Fire-Work Stands, of which the following is a specification.

My present invention relates to improvements in the construction of portable stands 10 for the discharge of sky-rockets and similar fire-works for pyrotechnic purposes.

Its object is to provide a simple, convenient, and effective device whereby the discharge of such fire-works may be accomplished 15 with entire safety and convenience by persons of limited skill.

In the accompanying drawings I have shown at Figure 1 in perspective, and at Fig. 2 in plan, a portable fire-work stand embodying my present improvements, which I will now proceed 20 to describe.

The stand itself consists of a table, A, journaled upon hinged or folding legs B B B, as shown, whereby the angle of each pair of legs 25 may be altered to raise or lower the stand, and also whereby the table and legs when not in use may be folded into the same plane, thereby saving space for packing and transportation.

30 In the table A is borne or supported a discharge-tube, C, of suitable diameter to receive the rocket or other similar projectile to be discharged. The lower or rearward portion of this tube C is cut away, as shown, to afford 35 access to the fuse of the projectile for its discharge.

By virtue of the hinged connection between the table A and its legs, before described, it is obvious that by changing the plane of the table A, which carries the discharge-tube C, the angle or inclination of this last toward the horizon can be varied, and the flight of the projectile thereby regulated at pleasure. The discharge-tube C incloses the rocket or projectile and effectually prevents its accidental 45 displacement or deviation at the moment of

firing, thereby preventing accidents, which often arise from this cause when open gutters or troughs are used.

If required, the table A may also be utilized for the discharge of stationary or non-projectile fire-works—such as Roman candles—by forming suitable sockets or holes in the table, as shown at *a a a a* in the drawings.

55 In practice I prefer to form the legs B B B and the table A of wood, on account of its lightness and cheapness, and the discharge-tube C of metal tubing, which I find it convenient to secure in the table A by friction alone, so as to permit of the withdrawal of the tube C for convenience in packing, transportation, &c.

For securing the legs and table so that they may be adjusted and folded, a bolt-headed 65 rod and screw-nut, D, may be conveniently employed, as illustrated in the drawings.

My improved portable fire-work stand as above described is simple and cheap in construction, and insures the accurate and safe 70 discharge of the rocket or other projectile for which it is intended.

I am aware that rocket-stands in which the rocket to be discharged lies within an open groove or gutter have been long known and 75 used, and I therefore make no claim, broadly, to cover such devices.

I claim—

The portable fire-work stand herein described, consisting of the table A, discharge-tube C, borne or supported by the said table, and hinged or folding legs B B B, journaled to the said table, all substantially as set forth, and for the purposes herein specified.

80 In testimony whereof I have hereunto subscribed my name this 21st day of September, A. D. 1885.

HENRY C. WEEDEN.

Witnesses:

J. HENRY TAYLOR,
JAMES F. BLIGH.
